FIG. 5.

Patented Mar. 20, 1923.

1,448,780

UNITED STATES PATENT OFFICE.

NELSON D. WELLS, OF DAYTON, OHIO.

BURGLAR ALARM.

Application filed January 21, 1922. Serial No. 520,957.

To all whom it may concern:

Be it known that I, NELSON D. WELLS, a citizen of the United States, residing at Dayton, in the county of Montgomery and State of Ohio, have invented certain new and useful Improvements in Burglar Alarms, of which the following is a specification.

The principal object of my invention is to provide a simple and efficient burglar alarm that may be used in a building or an automobile to sound an alarm when a thief seeks to gain entrance thereto. My improved burglar alarm is portable, and may be easily placed in a position for operation by a door or other movable object.

In the accompanying drawings, Figure 1 is a side elevational view of my improved burglar alarm in its closed position. Figure 2 is a top plan view of the same with the lid removed. Figure 3 is a front end view of the device, partly broken away to reveal the ratchet and cartridge-holding mechanism. Figure 4 is a longitudinal, sectional view taken through the device, showing the cartridge discharging means. And Figure 5 is a side view of a door, showing my device in a position to be operated by the knob thereof.

Throughout the specification and drawings, similar reference characters denote corresponding parts.

Referring to the accompanying drawings for a detailed description of the preferred form of embodiment of my invention, the numeral 1 designates a trough-shaped metallic shell or casing to which there is hingedly secured a cover 2. Pivottally secured by a screw 3 to one side of the cover 2, is a hook 4 whose free end is adapted to engage a screw 5 secured to the casing 1, to firmly lock the cover thereto. (See Figure 1.)

Secured by means of screws 6, 6 within the metal casing 1, is an elongated cylindrical member 7 containing a side recess 8 in its front end to receive a cylinder 9. The latter contains axial holes 10 adapted to receive blank cartridges 11 which are exploded by means hereinafter to be described. (See Figures 2, 3 and 4.)

The cartridge holding cylinder 9 is fixedly secured on a rod 12 whose front end is received by a hole in the head portion 13 of the cylindrical member 7. Immediately behind the cartridge holder 9 there is an enlarged

portion 14 of the cylindrical member 7, through a hole in which the front end of the rod 12 also passes, the rear end of said rod projecting through a hole in the rear wall 15 of the casing 1. Fixedly secured to the rear end of the rod 12 is a finger-grip element 16 by means of which the rod may be rotated to turn the cartridge holder 9. (See Figures 1 and 2.)

Provided in the front wall 17 of the metal casing 1 is a hole 18 that communicates with a hole 19 in the head portion 13 of the elongated cylindrical member 7. The hole 19 is so located that its center will be on substantially the same circumference as the centers of the holes 10 in the cartridge holder 9, so that when the latter is rotated, the cartridges 11 contained in the latter holes may be successively brought behind the hole 18 for explosion. (See Figure 3.)

Provided in the periphery of the cartridge holder 9 are transverse notches 20, one for each hole 10. These notches are spaced apart a distance corresponding to that which exists between each two of the holes 10. Secured to one side of the cylindrical member 7 by means of a screw 21, is a flat spring pawl 22 whose nose portion is adapted to engage the notches 20 in the periphery of the cartridge holder 9 to prevent a rearward movement of the latter after it has been turned forward one notch. When the cartridge holder 9 has been turned clockwise one notch by the rod 12, it will bring one of the cartridges 11 to a position directly behind the hole 19, where it will be held by the pawl 22 until it is exploded by the means now to be described.

The cylindrical member 7 contains a longitudinal bore in which there is movable a striker rod 23 having a chisel-shaped front end 24 adapted to engage and explode the cartridge. Just behind its striking end 24, the rod 23 has an annular shoulder portion 25 that has a free longitudinal movement within the bore of the cylindrical member 7, to guide the chisel-shaped end 24 of said rod into engagement with a cartridge 11. The rear end of said rod has a rotative and longitudinal movement through an end piece 26 screwed into the rear end of the elongated cylindrical member 7. (See Figure 4.)

Encircling the striker rod 23 between the shoulder 25 and the end piece 26, is a coil spring 28. At its rear end the rod 23 termi-

nates in an offset portion 29 by means of which the rod may be pulled back, against the compression of the spring 28, to draw the chisel-shaped end 24 of said rod away 5 from the cartridge holder 9. (See Figure 4.)

Provided in the rear top portion of the front side of the casing 1, is an elongated notch 30 through which the offset portion 29 of the rod 23 is free to be moved rearwardly to a concave recess near the rear wall 15 of the casing. Into this recess the offset end 29 of the rod 23 is adapted to be turned, to hold the rod in its spring-compressing position, preparatory to its release for exploding the cartridge.

When the rod 23 is held in the latter position, the cartridge holder 9 is free to be rotated by the rod 12 to bring an unexploded cartridge 11 into a position to be engaged by the striker end 24 of the rod 23. In operation, the offset end 29 of the rod 23 may be drawn out of the concave recess at the end of the notch 30 by numerous means, among 20 which is the one now to be described. Referring to Figure 5, the numeral 31 designates a door to the knob 32 of which there is applied a gripping band 33 to which there is secured a horizontal turning member 34. To each end of the latter there is connected the free end of a string 35 which, at its lower middle portion, is secured to the offset end 29 of the rod 23 of a burglar alarm placed on the floor near said door. Now, when the knob 34 is turned, one end of the horizontal member 34 will be elevated to pull the offset end 29 of the rod 23 out of the recess at the end of the notch 30, whereupon the compressed spring 28 will be free to force the front end 24 of said rod against the cartridge 11 with sufficient violence to discharge it. (See dotted lines in Figure 4.) The sound resulting from the explosion of this cartridge will be sufficient to apprise persons in the vicinity, of the attempt of a thief to enter the building or automobile in which the device is placed.

After a cartridge has been exploded by it, 50 the rod 23 may be drawn back by its offset portion 29 to the recess which receives it. The cartridge holder 9 is then free to be turned by the rod 12 to bring an unexploded cartridge in direct line with the hole 19 and the longitudinal bore in the cylindrical member 7 for explosion by the front end of the rod 23 when its offset end 29 is again disengaged from said recess.

I do not wish to be limited to the details 60 of construction and arrangement herein shown and described, and any changes or modifications may be made therein within the scope of the subjoined claims.

Having described my invention, I claim:

65 1. In a device of the type described, the

combination with a casing, of a cylindrical member mounted therein containing a longitudinal bore, an operating rod rotatably mounted in said casing, a cartridge holder fixedly secured to said rod having a series 70 of axial cartridge-receiving holes, each one of which is adapted to be successively brought in direct line with the longitudinal bore in the cylindrical member to position a cartridge in front of said bore, a striker 75 rod slidable in said bore, means adapted to be compressed by the outward movement of the striker rod to force the front end of the latter into violent engagement with a cartridge in said holder to explode the 80 same, and means for holding said striker rod in its outermost position to permit the cartridge holder to be rotated by the first rod to bring an unexploded cartridge to a 85 position to be engaged by the front end of the striker rod.

2. In a device of the type described, the combination with a casing, of a cylindrical member mounted therein containing a longitudinal bore and having a recess in its front portion, an operating rod rotatably mounted in said casing, a cartridge holder fixedly secured to said rod for rotation in said recess, said cartridge holder having a series of axial cartridge-receiving holes, each 90 one of which is adapted to be successively brought in direct line with the longitudinal bore in the cylindrical member to position a cartridge in front of said bore, a striker 95 rod slidable in said bore, a shoulder on said striker rod, a spring encircling said rod between said shoulder and the rear end of the cylindrical member, adapted to be compressed by the outward movement of the striker rod to force the front end of the 100 latter into violent engagement with a cartridge in said holder to explode the same, and means for holding said striker rod in its outermost position to permit the cartridge holder to be rotated by the first rod 105 to bring an unexploded cartridge to a position to be engaged by the front end of the striker rod.

3. In a device of the type described, the combination with a casing, of a cylindrical 110 member mounted therein containing a longitudinal bore and having a recess in its front portion, an operating rod rotatably mounted in said casing, a cartridge holder fixedly secured to said rod for rotation in said recess, said cartridge holder having a series 115 of axial cartridge-receiving holes, each one of which is adapted to be successively brought in direct line with the longitudinal bore in the cylindrical member to position a cartridge in front of said bore, a striker 120 rod slidable in said bore, means for forcing said striker rod into violent engagement with a cartridge in said holder to explode it, said cartridge holder having transverse 125

notches in its periphery, and a spring pawl secured to said cylindrical member behind its recessed portion to engage the notches in the periphery of the cartridge holder, to prevent a counter movement of the latter after it has been turned by the operating rod to bring an unexploded cartridge in front of the striker rod.

4. In a device of the type described, the combination with a trough-shaped casing, of an elongated cylindrical member mounted therein containing a longitudinal bore and having a recess in its front portion, an operating rod rotatably mounted in said casing at the side of the cylindrical member, a cartridge holder fixedly secured to said rod for rotation in said recess, said cartridge holder having a series of axial cartridge-receiving holes, each one of which is adapted to be successively brought in direct line with the longitudinal bore in the cylindrical member to position a cartridge in front of said bore, a striker rod having a rotative and slidble movement in said bore, a shoulder on said striker rod, a spring encircling

said rod between said shoulder and the rear end of the cylindrical member, adapted to be compressed by the outward movement of the striker rod to force the front end of the latter into violent engagement with a cartridge in said holder to explode the same, an offset rear end on said striker rod, and a wall on said casing having a longitudinal notch in its top rear portion through which the offset rear end of the striker rod is free to move rearwardly to compress said spring, said wall having a recess at the end of said notch to receive the offset rear end of the striker rod to hold it in its outermost position, whereby the cartridge holder may be rotated by the operating rod to bring an unexploded cartridge to a position to be engaged by the striker rod when its offset end is forced out of the recess at the end of said notch.

In testimony whereof I have hereunto set my hand this 20th day of January, 1922.

NELSON D. WELLS.

Witness:

HOWARD S. SMITH.
